[57] **CLAIM**

The ornamental design for a single use catheter device, as shown and described.

DESCRIPTION

FIG. 1 is a front elevational view of a single use catheter device; showing my new design;

FIG. 2 is a top plan view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a front elevational view similar to FIG. 1 of an alternative embodiment of the catheter device;

FIG. 8 is a top plan view of the alternative embodiment of FIG. 7;

FIG. 9 is a rear elevational view of the alternative embodiment depicted in FIG. 7;

FIG. 10 is a left side elevational view of the alternative embodiment depicted in FIG. 7; and

FIG. 11 is a right side elevational view of the alternative embodiment depicted in FIG. 7.

Fig. 1.

Fig. 2.

Fig. 3.

Fig. 4.

Fig. 5.

Fig. 6.

Fig. 7.

Fig. 8.

Fig. 9.
